tion of Illinois

Application January 10, 1946, Serial No. 640,189

5 Claims. (Cl. 20—52)

1

The present invention relates generally to sliding windows, and more particularly to a double-hung window unit or assembly, which may be easily inserted into and removed from a suitable window opening. More specifically, the present invention may also provide a "weather stripped" window sash.

It has long been a practice to employ sash cords and weights, or window balances, for sliding sash. Sash hung to slide in runs or slide-ways, conventionally defined by suitable stop-strips forming part of the window casing, is commonly found in the conventional double-hung windows. There are many disadvantages to such conventional windows with sash weights or balances, and with such channel-form slide-ways. Windows must be washed from the outside, or otherwise with considerable difficulty or danger from the inside. Such sash on the outside cannot be washed while a storm window exteriorly thereof remains in place. When the glass is broken and must be replaced, the work must be done on the outside or else the entire sash must be removed from the window with considerable expenditure of time and labor to remove it and to reinstall it. If it is the upper sash that is to be removed, the lower sash must be first removed. The conventional type of vertical sliding window is also expensive to construct and to install, compared to the improvements of the present invention.

The present invention offers many advantages, and overcomes many of the above mentioned defects found in the conventional window. The new structure is less expensive to manufacture, to install, and to repair. The new window may be installed with a great saving of time over that required to install the conventional window. The new structure is not wholly limited to new assemblies of frame and sash, and by modifications hereinafter referred to, conventional frames with their conventional sashes may be converted to embody the present invention with practically all of its advantages.

It is an object of the present invention to provide a simple and an improved assembly of window frame and sliding sash.

It is a particular object to improve the vertical double-hung window structures, not only to lower first cost, but to add advantages in use.

It is an object to provide means for forming slide-ways for the sliding sash which means may provide a weather-proof union between the sash and frame.

It is another object to provide a unit, or assembly, including the sliding sash, for fitting easily into the window frame therefor, and easily

removable therefrom; and where desired to provide a hanging connection or linkage between said assembly and said frame to permit temporary removal of the assembly from the frame for the purpose of cleaning or repairing.

Other and ancillary objects and advantages of the present invention will become apparent from the following description and explanation of the invention as illustrated in the accompanying drawings, in which:

Fig. 1 is a face view of an outside window from the interior side.

Fig. 2 is a vertical cross-section of the line 2—2 of Fig. 1.

Fig. 3 is a horizontal cross-section, enlarged and fragmentary, on the line 3—3 of Fig. 1 looking downwardly toward the sill, and showing in cross-section the sash stiles and the slide-way structures therefor.

Fig. 4 is a view similar to Fig. 2 showing a sash-carrying assembly displaced toward the interior of the room and mounted by a linkage connection to the window frame.

Fig. 5 is a vertical elevation of the slide-way-forming structure showing the linkage which appears in Fig. 4.

Fig. 6 is an enlarged cross-section of the structure shown in Fig. 5 on the line 6—6 thereof.

Fig. 7 is an enlarged fragmentary vertical cross-section taken on line 7—7 of Fig. 1 showing the lower sash slightly raised from the sill, showing a friction grip device, and showing a weather strip construction beneath the lower sash rail.

Fig. 8 is an enlarged fragmentary cross-section of the lower sash and parts lateral thereto, showing in particular the construction of a friction gripping means set into the sash stile, said view being on the line 8—8 of Fig. 1.

Fig. 9 is a horizontal enlarged fragmentary view in cross-section on the line 9—9 of Fig. 4 showing the connection of the hanging link to the window frame side.

Fig. 10 is a fragmentary perspective view of weather stripping for mounting as shown on the top and bottom rails of the upper sash and on the bottom rail of the lower sash.

Fig. 11 is an end view of a conventional window sash bored and slotted for a sash cord, and subject to modification to embody the present invention as shown in Figs. 12 and 13.

Figs. 12 and 13 represent the conventional window sash of Fig. 11 routed out along the entire face of the stile and fitted with an insert slotted for a monorail forming part of the slide-way-forming structure.

The present invention requires a wall having

a window opening therein, which opening is commonly supplied as a prefabricated frame to be mounted in a wall. Conventional prefabricated frames of the type long supplied for the common double-hung window with upper and lower sliding sashes, may be modified for cooperation with the sash-carrying unit or assembly of the present invention. Such unit or assembly is a structure which may be readily mounted in and removed from the opening of the window frame, to complete the window. Where the conventional vertical sliding sashes are involved, sash-holding means may be provided of a type avoiding the use of sash weights or spring balances. Where the window structure is such that the sash may slide horizontally, no sash-holding means is required.

The window frame is such that it provides two parallel frame members between which a sash slides. Commonly these are the vertical members, and for this reason the invention is illustrated by reference to a vertical double-hung window. From this description and explanation it will be obvious to those skilled in the art how the illustrated structure may be differently embodied and modified without departing from the spirit and scope of the invention as set forth in the appended claims.

The sash unit, or assembly, hereinafter referred to as the "sash unit," comprises means forming two parallel slideways for each sash, and where there are two slideable sashes, there is at each frame side on which the sashes slide, slide-way-forming-means to provide adjacent and parallel slide-ways. The nature of the slide-way may vary greatly in detail. It may be the conventional channel in which the sash edge slides, as illustrated by the space between the conventional vertical parting stop and the inner or outer vertical stops in conventional double-hung windows. The slide-way may be any sort of track or slide-rail on which the window slides with a guided relation. Preferably the slide-way is a monorail for each sash, fitting into a groove in the edge face of the sash. With such a monorail, the conventional stop members which form the conventional slide-channel, may be dispensed with insofar as they need serve as guides for the sliding. However, such stop members may be retained for other reasons, for example, conventional appearance for the new window of the present invention, or, with respect to the parting stop, to space the adjacent sash stiles, thus to permit use of the conventional wider sash top-rails reversely tapered for wedging together in the closed position of the sashes.

A sliding interlocking relationship may exist between each sash and the slide-way-forming means. One function of this relationship is to permit the sashes and said means, at each sliding edge of the sashes, to be joined together in their intended sliding relationship as an integral unit. This unit, referred to above as the "sash unit," is then easily inserted into a suitable window opening therefor, and then by merely securing the slide-way-forming means to the frame, the window may be complete with its slideable sash.

The preferred interlocking relationship is effected as a modification of the preferred monorail, by constructing the monorail and the groove, in a manner to interlock the sliding parts. This may be done by angular conformations or enlargements in the monorail. Preferably, it is effected by a terminal enlargement on a thinner

supporting web of the monorail, similar to the conventional locomotive rail, and having in the sash a receiving-groove to interlock with it. One manner of doing this is illustrated hereinafter.

The preferred sash-holding means merely prevents sliding of the window by the force of gravity, and it is not intended to counterbalance the weight of the sash. The holding-means may be any conventional structure for holding the sash against sliding by positive engagement, or by a frictional engagement, for the purpose. The preferred location for such a holding means is a concealed one within the sliding stile of the sash, and it is preferably arranged frictionally to engage the preferred monorail, and is preferably constructed to permit adjustment of the degree of frictional engaging pressure, in part to compensate for the effects of time, such as wear in use. A suitable and an improved form of such means is described hereinafter.

The slide-way forming means for each sash may take many forms, and be of many materials. It may be a composite structure, of several parts united or not, or an integral structure. Preferably, the two adjacent slide-ways at each side of the frame for the two sashes, are embodied in a single member. The preferred structure for such a member is a sheet-metal conformation, providing the desired slide-ways, or the preferred monorail, and any desired stop-like members, or any desired trim strips, or sealing means against the elements, such as wind and rain. Stainless steel may be employed, or zinc sheet, or other non-corrosive metal or alloy.

A useful hanging means, or a linkage, is optional, and highly advantageous, for example, to permit the sash unit to be moved in one direction as into the interior of a house from the window opening, in order to expose the external face of the sash unit for easy access from within the room. Such linkage means also serves to guide the sash unit from such displaced position back into its normal position in the frame. When the sash unit is thus exposed by such movement on the linkage means, the window may be conveniently washed from the inside. In winter this may be done advantageously while a storm window remains in place. Also when the sash unit is thus exposed, one or both of the sashes may be readily removed, endwise of the slide-ways where the interlocking relation exists, for example, to permit renewing glass in a sash. Such hanging means, or linkage, to permit such motion, is connected at one end of the sash unit and at the other end to the window frame. A suitable linkage or hanging means for these purposes is described hereinafter.

Numerous other improvements or structures may be added to the essential parts of the window structure as above referred to, and these will add to the value of the window. Some of these are illustrated and described along with the essential elements of the present invention.

In Figs. 1, 2 and 3, certain conventional structural portions of a window are designated as follows: A window frame structure has the head jamb 10 and opposite thereto the sill 11, with side jambs 12 and 13 extending vertically between them. Externally of said frame, as shown in Fig. 2, is the side casing 14, head casing 15, and above the latter a drip cap 16. There are blind stops 17 at the head and sides over the edges of the head and side jambs. Internally of the window frame there is the stool 18 and

5

beneath it the conventional apron 19. Upwardly from the stool rises the vertical window trim members 20 extending to the cap trim 21.

The upper window sash comprises a frame 22 and window glass 23. The frame 22 consists of upper top rail 24, check rail 25, and stiles 26 and 27.

The bottom sash has sash frame 29 and glass 30. The sash frame 29 consists of check rail 31, bottom rail 32, and stiles 33 and 34.

All of the foregoing parts are conventional. Between the upper and lower sash and in the head jamb there is a top horizontal parting stop 36, which departs from conventional structure in that its ends stop short of the side jambs 12 and 13, and thereby provide clearance spaces 37 and 38 having the function of permitting edge-wise insertion of movable vertical structures through the clearance space, to lie alongside the side jambs.

In Fig. 6 there is shown in cross-section means for forming slide-ways for the sash, which means is illustrated as a vertically elongated integral unit formed of sheet metal. It is referred to herein as vertical side member 40 for the right hand side of the window in Fig. 1 and as 44 when reversely constructed for the left hand side of Fig. 1. It may partake of many forms to provide slide-ways, and in the form particularly illustrated it has the following parts. The left hand edge of the sheet metal is turned over to form a blunt folded edge 42 which fits into a groove adapted to receive it, as more particularly shown in Fig. 3, said groove being designated 43 located in the blind stop 17, and having its opening directed alongside the face of the side jamb, which guides the edge 42 into groove 43. To the right of said folded edge or flange 42, there is a doubled-back loop of metal forming a channel side or stop designated 44 which is companion to a channel side 45 formed in the sheet metal in shaping the metal into a rectangular structure serving as a conventional parting stop 46. The bottom of the channel is formed by the sheet metal portions 47 and in this channel the upper sash 22 slides. However, the middle of the channel contains an upstanding portion serving as a track-rail 48 with a rounded edge or bead 48a of circular cross-section, which structure is also herein termed a monorail. Said monorail fits into a groove in the sash, later described. Thus, the sash rides in a slide-way which functions by reason of the channel sides 44 and 45 without the monorail 48, or functions with the monorail 48 alone without the channel sides 44 and 45.

The sheet metal forming the side member 40 extends toward the interior of the window from the parting stop 46 by forming a comparable channel for the lower sash, said channel having channel sides 49 and 50 and a like monorail 51 with bead 51a.

The channel side 50 may be extended forwardly toward the interior of the room in order to provide interior finish for the window, comparable to the conventional inside stop. As illustrated a conventional vertical wood strip or trim 53 is shown in Fig. 6, and it is anchored to the sheet metal by reversely bending the channel side 50 to provide a channel structure having bottom 54 and other channel side 55, which latter fits into a groove in the trim strip 53. The dotted line 56 in trim strip 53 in Fig. 6 indicates screws which secure the trim strip 53 to the side jambs as above shown in Fig. 3. Thus by mounting the

6

trim strips 53 to the side jambs when the side members 40 and 41 are placed against the jamb with the flange 42 in the groove 43 of the blind stop 17, the whole structure is rigidly and fixedly mounted, and provides a slide-way for each sash. This structure is duplicated on both vertical sides of the window, as shown. A number of mounting screws 56 are provided according to the vertical span of the window opening.

10 It is observed that the line of the channel bottoms 47 for the slide-ways is inwardly of the opening from the line of the edge 42 and channel 54 to provide space 57 (Fig. 3) for a mounting link, later described.

15 Each window sash 22 and 29 is correspondingly grooved to slide upon monorails 48 or 51. This is described in detail with reference to the upper sash 22 as best shown in cross-section in Fig. 3.

With respect particularly to the monorail 48 20 and its circular bead 48a, there is provided in the sliding edge face of the sash stile 27 (Fig. 3) a groove 58 wide enough to slide readily on the web of monorail 48, and enlarged at the bottom in a circular enlargement to receive and slide readily 25 around the bead 48a. The closeness of fit between the monorail and the groove is such as to form a substantially closed passageway thus to wind-proof the structure around the edge of the sash. With such wind-proofing structure the 30 sash edge may have considerable clearance between the grooved face and the channel bottoms 47 of the slideway, and also there may be considerable looseness in the fit of the stile between the channel sides 44 and 45. The fit of the monorail 35 in the groove can be made to control the clearance between the grooved face of the stile and the channel bottom 47, and the latter will move to a limited extent as the sash may change its dimensional width. The clearance space 57 40 (Fig. 3) for the mounting linkage, thus serves additionally to prevent edge-wise binding of the sash. Thus, swelling of the wood of the sash will not lead to binding, when the guided sliding is effected by the monorail and groove.

45 Reference is made to Figs. 2 and 4 which more clearly show the check rails 25 and 31. These have the conventional cooperating tapered constructions, extending the rails beyond the flush faces of the stiles. In order to avoid the unconventional appearance of space between the stiles 50 of the upper and lower sashes, where the monorails serve as the effective sliding guides, the side member 40 is formed with a simulated parting stop 46. As a parting stop, it may be dispensed 55 with when the monorail is provided, but should the monorail be dispensed with, the parting stop 46 would perform its conventional stop function in conjunction with the channel side 44 for the upper sash, and with the channel side 50 for the lower sash. However it functions, utilization is made of the hollow space within the parting stop 46, to mount therein an anchorage for linking means which may be used to tie the vertical member 40, to the window frame. As shown, there is mounted within the parting stop a channel-shaped piece of metal 60 (Figs. 3, 5 and 6) 60 with one channel side 61 lying in or closing the open area of a portion of the channel-form parting stop 46, and having an opposite channel side 62 lying against the bottom of the channel-form parting stop 46, to which it is anchored by one or more countersunk screws 63. To the exposed channel side 61, which is flush with the adjacent 65 faces, is pivoted a link 64. At its opposite end

70 75

the link 64 carries an angle block or bar 65 pivoted at 66. Said bar 65 is shown in cross-section in Fig. 9 as sliding in a channel-form piece of metal 67. On its channel side 68 there is a 5 detent in the form of a flange 69 for a slidingly engaged short flange 70 on the bar 65, to prevent withdrawal of the parts facewise. The bar 65, therefore, slides vertically in the channel 67 which is mounted in a groove 71 in the side jamb 13. The groove 71 is comparable to the conventional groove provided in a conventional side jamb for the conventional parting stop. As shown, the groove 71 extends the full length of the side jamb 13, but this is not necessary, and results only from the use of a conventional side jamb. Screws 72 (Fig. 3) are shown for mounting the channel 67 within groove 71, as shown. By means of this linkage each vertical side member providing the slide-way, may be swung forwardly, as into a room, to the limit permitted by the link 64, which slides freely at one end vertically in the channel of the side jamb.

To prevent the sashes sliding freely in their sideways formed by the two opposing side members 40 and 41, there is provided a suitable holding means. As illustrated, the holding means is not positive in action, but is such as to provide sufficient friction to avoid any undesired sliding of the sash. Concealed means for this frictional gripping is preferred. Simple means is also provided to adjust or correct the degree of friction exercised. In Fig. 3 in the lower sash 29, there is shown in dotted lines two block-like members 73, and associated with them adjusting screws 74 of which the heads ride in metal sockets of washer-like members 74^a on the face of the sash. The blocks 73 are better shown in Figs. 7 and 8 as a bifurcated member having the base 75 and the two gripping fingers 75^a and 75^b. A suitable gripping structure is formed of a hard maple wooden block which is slit to provide the spaced cut 76, the bottom of which is enlarged in a circular form 77 to prevent a wood-splitting extension of the cut. Toward the end of the gripping fingers there is also a second enlargement 78 located and shaped to grip the beads 48^a or 51^a on the described monorails. These wood blocks are merely set into recesses cut into the sash stiles from the sliding edge-face of the stile. The adjusting screw 74 is threaded into the furthest finger 75^a, and passes freely through the other finger 75^b. Thus, by tightening the screw the finger 75^a is pressed against the bead, with or without pressure from the finger 75^b according to the structure and resiliency of the block 73. It is preferred that the finger 75^b be substantially immovable between the monorail and the face of its socket having the adjusting screw, thus to provide backing for the monorail to resist pressure of the movable finger 75^a on the monorail.

With the two sashes threaded onto their monorails, and with the gripping devices set to hold the sashes from sliding against gravity, the two side members 40 and 41 and the two sashes 22 and 29 may be assembled into a four piece assembly or unit. First consider that the linkage 64 is not provided or is removed. The sash unit thus consisting of the two side members 40 and 41 and the two sashes is a substantially rigid unit. When this unit is assembled with the lower sash raised and the upper sash lowered from closed position as shown in Fig. 4, the whole unit may be bodily inserted into the window frame opening described, up to the blind stops 17. The tops

5 of the side members 40 and 41 pass the ends of the so-called top horizontal parting stop 36, and the end flanges 42 of the side members 40 and 41 enter and bind tightly into the grooves 43 in the corresponding blind stops, thus to provide a wind proof seal. To secure the structure in place the screws 56 are entered into the side jambs 12 and 13 to hold the interior trim strips 53 in place, thus binding the sheet metal to the jambs.

Then the windows may be moved into closed position as shown in Fig. 2. In this closed position of each sash it is possible to remove the mounting screws 56 without in any way rendering the structure removable. The structure cannot be removed at all because the top rail 24 of the upper sash is obstructed by the so-called parting stop 36, and the lower end of the sash unit is obstructed by the bottom rail 32 of the lower sash lying behind the stool 18. However, on opening both sashes to clear these obstructions, and with screws 56 removed, the whole sash unit may be withdrawn.

In order to facilitate removal of the sash unit from the window opening without detached removal, the described links 64 are provided to permit tilting of the sash unit forwardly on the ends of the trim strips 53, which are slightly rounded at 80 to provide a fulcrum on a limited area of the stool. The fulcrum area may be protected against wearing away by inlaying a metal plate over the area covered by the end of the trim strip 53 as it rocks. As the sash unit is tilted forwardly, it is tied to the frame by the link 64, and the bar 65 rises in its channel 67. Thus, it is clear that the channel 67 is sufficiently elongated so that its lower end will retain the bar 65 when the link 64 is vertical in the entered position of the sash unit.

Auxiliary structures for weather proofing the sash may be provided as desired. In Fig. 10 there is shown spring metal weather stripping suitable for the purpose. It has a crimped mounted flange 82 and a V-shaped body 83. The angle between the flange 82 and the body 83 may be changed according to the angular location of the weather stripping. This weather stripping is illustrated in the drawings as located at the bottom of the lower sash rail 32, in which location the V-shaped body 84 presses against the sill 11. There is also a strip 85 located on the check rails, being mounted, Fig. 4, on the check rail 25 of the upper sash to seal the space between it and the check rail 31 of the lower sash. A like strip 86 is also mounted at the top of the top rail 24 of the upper sash.

The invention is capable of being embodied in conventional windows by very simple alterations in the conventional structures. In the conventional window the vertical blind stops, like stops 17, are merely grooved to provide a groove like 43 to receive a flange 42 of the vertical side members which are to be added to the conventional window to cover the normal side jambs. The conventional vertical parting stops are removed from the groove normally provided therefor in the conventional side jambs. The top parting stop is cut away at its ends to provide clearance spaces like spaces 37 and 38 in Fig. 1, for the tops of the side members to be added. Where a mounting linkage is desired, a channel structure 67 is mounted in the grooves which are exposed when the vertical parting stops are removed from the side jambs.

The conventional sash 90 (Fig. 11) having the bore 91 and slot 92 for sash cord is readily modi-

fied, as to each sash, for the present invention. The rope slot is merely extended and widened by routing out at 93 the whole edge face of the sash stile and planing down the face sufficiently to permit entry of the side members providing the slide-ways. A hole is chisled into the stile for the insertion of a gripping block 94, similar to that shown in Fig. 8, and the adjusting screw 95 is provided as shown in Fig. 12. Into the routed out space 93 (Fig. 13) on the face of the stile is secured a corresponding insert 96 which has a keyhole-like slot 97 therein to receive the monorail therefor provided in the side member.

Numerous advantages other than those indicated above will now be more apparent from the above description. The side jambs of the frame are completely covered from sight and from exposure to the weather. They need no paint. Hence, grades of lumber lower than is conventional for windows having exposed side jambs may be used. Paint need not be applied at any place which would lead to sticking of the sashes, excluding the sill, since the sash runs, being of metal as described, need no paint. Where the inner faces of the blind stops 17 are exposed and face the sashes, the unexposed and paintable portion is spaced from the upper sash frame by the thickness of the channel side 44. The painting of the sashes may lead to flow of paint into the interfacial space between the sashes and the sides of the channels in which the sash slides. However, where the described monorails are present, and are the effective slide-way and guide for the sash, there can be considerable clearance space (not shown in the drawings) between the sashes and the channel sides comprising the parting stop 46, the channel side 44, and the channel side 50. When such clearance is present the extension of paint on the sash into such clearance space will not lead to any binding of the sash.

The parts are completely protected from seepage of rain, and there are no upstanding portions or dams for providing weather protection of such character as have heretofore caused the collection of water, thereby to induce rot.

To clean the window from the inside, the sash unit is readily moved out into the position of Fig. 4. Then each sash may be brought separately to upper position for cleaning from the inside of a room. If new glass is to be inserted, each sash may be removed endwise of its slide-way upwardly in Fig. 4, while the side members 40 and 41 remain in hanging position as shown.

Although the invention has been illustrated particularly for vertical sliding windows, it is understood that it is equally adaptable for horizontal sliding windows, in which case the gripping devices may be dispensed with if desired.

Numerous modifications and departures from the illustrated forms are contemplated as falling within the scope of the invention as expressed in the appended claims.

I claim:

1. A window-closure assembly comprising in combination, two spaced parallel vertical sash guides each having two independent slideways for two sashes and having substantially flat outer faces positioned parallel to each other in assembled relation with sashes, whereby the assembly thereof with sashes may be moved in and out of a window opening in a wall to position said sash guides over and substantially adjacent to flat side walls of said opening, two adjacently slideable sashes between said guides holding them to-

gether in fixed horizontal spaced relation, each sash being slideable in one of said slideways, an interlocking tongue and groove connection between each sliding edge of a sash and the corresponding guide, said connection permitting sliding the sash edgewise along the guides and serving to hold the guides and sashes in assembled relation, and holding means for holding the guides and sashes in fixed positions.

2. A window-closure assembly comprising in combination, two spaced parallel vertical sash guides each having two independent slideways for two sashes and having substantially flat outer faces positioned parallel to each other in assembled relation with sashes, whereby the assembly thereof with sashes may be moved in and out of a window opening in a wall to position said sash guides over and substantially adjacent to flat side walls of said opening, two adjacently slideable sashes between said guides holding them together in fixed horizontal spaced relation, each sash being slideable in one of said slideways, an interlocking tongue and groove connection between each sliding edge of a sash and the corresponding guide, said connection including a tongue on the sash guide having a longitudinal web and a retaining extension on the web, and the groove in the sash being formed slidably to engage said extension to hold the sash guide and sash together in sliding relation against withdrawal of the tongue from the groove, and holding means for holding the guides and sashes in fixed positions and maintaining the sashes and guides as a substantially rigid assembly.

3. A window-closure assembly comprising in combination two spaced parallel vertical sash guides each having two independent slideways for two sashes and having substantially flat outer faces positioned parallel to each other in assembled relation with sashes, whereby the assembly thereof with sashes may be moved in and out of a window opening in a wall to position said sash guides over and substantially adjacent to flat side walls of said opening, two adjacently slideable sashes between said guides holding them together in fixed horizontal spaced relation, each sash being slideable in one of said slideways, an interlocking tongue and groove connection between each sliding edge of a sash and the corresponding guide, said connection including a tongue on the sash guide having a longitudinal web and a retaining extension on the web, and the groove in the sash being formed slidably to engage said extension to hold the sash guide and sash together in sliding relation against withdrawal of the tongue from the groove, and a sliding frictional holding means carried by each sliding sash frictionally to grasp the tongue of said connection and resisting sliding movement by the influence of gravity and maintaining the sashes and guides as a substantially rigid assembly.

4. A window structure comprising guide means providing a slideway for a window sash, said means having a tongue entering and slideable in a groove in the edge of said sash, a sash slideable in said slideway and having a groove slidably fitting said tongue, a friction holding device in the form of a bifurcated insert mounted in an opening therefor in the said grooved edge of said sash and extending well inwardly from the base of said groove whereby to provide resilient legs extending from the innermost base portion of said insert toward and beyond the base of said groove, the inner faces of said legs serving in part as the side walls of the groove to engage the

11

tongue, and threaded adjusting means connecting said legs at a region inwardly from said groove for adjusting the relative positions of said legs to vary the frictional engagement of said legs on said tongue.

5. A window structure comprising guide means providing a slideway for a window sash, said means having a tongue entering and slideable in a groove in the edge of said sash, a sash slideable in said slideway and having a groove slidably fitting said tongue, a friction holding device in the form of a bifurcated insert mounted in an opening therefor in the said grooved edge of said sash and extending well inwardly from the base of said groove whereby to provide resilient legs extending from the innermost base portion of said insert toward and beyond the base of said groove, the inner faces of said legs serving in part as the side walls of the groove to engage the tongue, and threaded adjusting means extending from a retaining head at the face of said sash inwardly through the nearer leg and into the other leg in threaded engagement arranged to adjust the

12

relative positions of said legs to vary the frictional engagement of said legs on said tongue.

WILLARD H. RUNDQUIST.
